US0D1114209S

(12) **United States Design Patent** (10) Patent No.: **US D1,114,209 S**
(45) Date of Patent: ** Feb. 17, 2026

(54) **FOLDABLE POTTY SEAT**

(71) Applicant: **Zhejiang Jike Industry & Trade Co., Ltd.**, Jinhua (CN)

(72) Inventor: **Yihua Zhang**, Jinhua (CN)

(73) Assignee: **Zhejiang Jike Industry & Trade Co., Ltd.**, Jinhua (CN)

(**) Term: **15 Years**

(21) Appl. No.: **29/959,059**

(22) Filed: **Aug. 23, 2024**

(51) LOC (15) Cl. **23-07**

(52) U.S. Cl.

USPC **D23/311**

(57) **CLAIM**

The ornamental design for a foldable potty seat as shown and described.

DESCRIPTION

FIG. 1 is a front right perspective view of a foldable potty seat showing my new design;

FIG. 2 is a front left perspective view of the foldable potty seat as shown in FIG. 1;

FIG. 3 is a front view of the foldable potty seat as shown in FIG. 1;

FIG. 4 is a right-side view of the foldable potty seat as shown in FIG. 1;

FIG. 5 is a rear view of the foldable potty seat as shown in FIG. 1;

FIG. 6 is a left-side view of the foldable potty seat as shown in FIG. 1;

FIG. 7 is a top view of the foldable potty seat as shown in FIG. 1;

FIG. 8 is a bottom view of the foldable potty seat as shown in FIG. 1;

FIG. 9 is a front left perspective view of the foldable potty seat in a semi folded state;

FIG. 10 is a rear left perspective view of the foldable potty seat in a semi folded state;

FIG. 11 is a front right perspective view of the foldable potty seat in a folded state; and,

FIG. 12 is a front left perspective view of the foldable potty seat in a folded state.
